UNITED STATES PATENT OFFICE.

EMMETT B. QUICK, OF COMSTOCK, TEXAS, ASSIGNOR OF ONE-HALF TO
ALFRED A. NEWELL, OF COMSTOCK, TEXAS.

NECK-YOKE CENTER.

No. 811,953.

Specification of Letters Patent.

Patented Feb. 6, 1906.

Application filed March 3, 1905. Serial No. 248,308.

To all whom it may concern:

Be it known that I, EMMETT B. QUICK, a citizen of the United States, residing at Comstock, in the county of Valverde and State of Texas, have invented new and useful Improvements in Neck-Yoke Centers, of which the following is a specification.

This invention relates to neck-yoke centers.

The objects of the invention are to improve, simplify, and strengthen the construction of such devices.

With the foregoing and other minor objects in view, which will appear as the description proceeds, the invention resides in a neck-yoke center comprising a tubular member adapted to fit the vehicle-tongue and having an inclined collar thereon, a protecting-piece, preferably formed of leather, surrounding the tubular member and resting against the inclined collar, an irregular washer having a thickened and beveled upper portion, said washer surrounding the tubular member and resting against the protecting-piece, and a removable collar surrounding the tubular member and holding the irregular washer in position.

The invention also resides in the particular combination and arrangement of parts and in the precise details of construction hereinafter described and claimed as a practical embodiment thereof.

In the accompanying drawings, forming part of this specification, Figure 1 is a side elevation of a vehicle-tongue, showing the improved neck-yoke center applied thereto. Fig. 2 is a front view of the improved device. Fig. 3 is a vertical central section thereof.

Like reference-numerals indicate corresponding parts in the different views.

The reference-numeral 1 indicates a vehicle-tongue of usual form and construction. Fitted upon the tongue 1 is the tubular member 2 of the improved neck-yoke center. The tubular member 2 is provided with an inclined collar 3, against which rests a leather protecting-piece 4, which is squared at its upper end, as shown in Fig. 3. The protecting-piece 4 surrounds the tubular member 2 and is prevented from rotating accidentally thereon by means of a pin or projection 5, said pin or projection being connected with the inclined collar 3 and being pointed, so as to bite into said protecting-piece. Surrounding the tubular member 2 and bearing against

the protecting-piece 4 is an irregular washer 6, which is thickened at its upper end and is beveled, as shown at 7. A removable collar 8 is held upon the tubular member 2, preferably by means of screw-threads 9, said movable collar 8 resting against the thickened washer 6 and holding said washer securely against the protecting-piece 4. The removable washer 8 is held against accidental displacement from the tubular member 2 by any suitable lock-nut means, such as a screw 10, which extends into a suitable bore between the threads of the removable collar 8 and the threads of the tubular member 2. The removable collar 8 preferably is square and is beveled, as shown at 11, thus forming a continuation of the beveled portion of the thickened washer 6.

If desired, the tubular member 2 at its rear end may be extended beyond the inclined collar 3, as shown at 12, in order that said tubular member may secure a stronger or more lengthened grip upon the vehicle-tongue, thus strengthening the entire device.

In using the improved neck-yoke center it will be understood by those familiar with the art to which the invention relates that the tab of the neck-yoke is fitted over the end of the vehicle-tongue and that said tab and neck-yoke rest against the protecting-piece 4.

Minor changes in the precise embodiment of invention illustrated and described may be made within the scope of the appended claims without departing from the spirit of the invention or sacrificing any of its advantages.

Having thus fully described the invention, what is claimed as new is—

1. A neck-yoke center comprising a tubular member, an inclined collar thereon, a protecting-piece surrounding the tubular member and resting against the collar, a washer varying in thickness and surrounding the tubular member, said washer abutting against the protecting-piece, and a collar movably engaging the tubular member and bearing against the washer.

2. A neck-yoke center comprising a tubular member having an inclined collar thereon, the rear end of the tubular member extending beyond the inclined collar, a pointed projection upon the inclined collar, a protecting-piece having a squared upper end, said protecting-piece surrounding the tubular mem-

ber and resting against the inclined collar and pointed projection, an irregular washer having a thickened and beveled upper portion, said washer surrounding the tubular member and resting against the protecting-piece, a removable squared and beveled collar screwed upon the tubular member and holding the irregular washer in position, and a screw extending between the removable col-

lar and the tubular member for locking said collar in position.

In testimony whereof I affix my signature in presence of two witnesses.

EMMETT B. QUICK.
